UNITED STATES PATENT OFFICE.

JOHN R. BAUMANN, OF RED WING, MINNESOTA.

BUILDING-BLOCK.

1,356,591.

Specification of Letters Patent. Patented Oct. 26, 1920.

Application filed September 24, 1919. Serial No. 325,926.

To all whom it may concern:

Be it known that I, JOHN R. BAUMANN, a citizen of the United States, residing at Red Wing, in the county of Goodhue and 5 State of Minnesota, have invented certain new and useful Improvements in Building-Blocks; and I do hereby declare the following to be a full, clear, and exact description of the invention, such as will enable others 10 skilled in the art to which it appertains to make and use the same.

The object of the invention is to provide a building block of such a construction as to provide for an overlapping break-joint 15 relation with similar blocks in the same and also in adjacent courses of the structure, and also for providing an interlocking relation with similar blocks both in the same and the adjacent courses so that in the erection and 20 formation of buildings, silos, elevator shafts, drains, sewers, water mains, culverts, and the like the use of cement or plaster may be dispensed with as a means of maintaining the proper relation of the building blocks, 25 the use thereof, if employed, being merely to serve as a filling or packing for the joint to insure the production of an air-tight structure; and furthermore it is the object of this 30 invention to provide an improvement or development of the principle of building block construction disclosed in my co-pending applications, numbered 227,093 filed April 6, 1918, and 275,349 filed February 6, 1919, to the end that the advantages secured by the 35 building blocks shown in said former applications in relation to the interlock secured between the elements of a single course may be extended to the courses respectively above and below or at opposite sides of each course, 40 so that the resulting structure, in effect, shall have the qualities and characteristics, in so far as offering resistance to either internal or external pressure, of a unitary device, or 45 of a wall consisting of a single block of which all of the elements are integrally related and united.

Further objects and advantages of the invention will appear in the course of the following description of a preferred embodiment thereof, it being understood however that changes in form, proportion and details 50 may be resorted to within the scope of the claims without departing from the principles involved.

In the drawings:

55

Figure 1 is a side view and Fig. 2 is a horizontal sectional view of a section of wall constructed of the blocks.

Fig. 3 is a perspective view of one of the line blocks employed in the construction of 60 the body portion of the wall.

Fig. 4 is a similar view of a block designed for use in the construction of a device having a curved or cylindrical wall.

Fig. 5 is a similar view of a line block in 65 which the offset or shoulder between the members is arranged in a slightly different relation to the members, to wit, on a transverse medial line as distinguished from the diagonal line of the offset or shoulder as 70 shown in Figs. 3 and 4.

Figs. 6 and 7 are perspective views respectively of blocks, also indicated in Figs. 1 and 2, and hereinafter referred to specifically as a key-block and a corner block, 75 wherein the offset or shoulder is arranged in the same relation to the members as indicated in the forms shown in Figs. 3 and 4.

Fig. 8 is a plan view of a line block showing optional planes of offset between block- 80 members.

Each block comprises two identically constructed members preferably cast or molded to form a unitary or integral structure and which may be regarded as meeting and being united either on the transverse medial plane or line indicated by the dotted line A—A of Fig. 8, or the plane indicated by the dotted line B—B of Fig. 8, or upon the longitudinal medial plane indicated by the 85 dotted line C—C of Fig. 8. Each of these members is provided with interlocking elements for engagement with corresponding elements on the adjoining block in the structure, and one of the elements of each block 90 is offset from the other member on one of these meeting or uniting planes, the direction of offset being parallel with the wall face surfaces D of the block or perpendicular to the course face surfaces E thereof to 100 form shoulders 10. In the construction of line blocks indicated in detail in Fig. 3, the identically constructed members are represented as meeting upon a diagonal plane indicated by the offset shoulder 10 disposed 105 diagonally to the transverse and longitudinal medial lines of the block, each of said members having a wall face surface D and

an inner longitudinal surface provided with male and female interlocking elements 11 and 12. Also the inner end of each block-member disposed near the transverse medial line of the block is provided with male and female interlocking elements 13 and 14 while the outer or remote ends of said block members are provided with male and female interlocking elements 15 and 16. When a 10 block of this construction is arranged in a wall structure in interlocked relation with other blocks of the same or similar structure, it will be seen that both transverse and longitudinal interlocking relation is established 15 between said adjoining or related blocks and moreover, due to the fact that one member of each block is offset from the other member in a direction parallel with the wall face surfaces or perpendicular to the course 20 face surfaces there is an interlock between the course in which said block is located and the courses above and below the same.

In the corresponding construction shown 25 in Fig. 4 the only difference consists in the fact that the block as a whole is given a slight curvature upon a radius adapting it to be used in the construction of an arched or cylindrical wall such as may be preferred in the construction of silos, drains, culverts 30 and the like.

In the construction shown in Fig. 5 the only difference resides in the fact that the offset between the members is made on a plane corresponding with the transverse 35 medial line of the block instead of upon a diagonal line as indicated in Fig. 3. Figs. 6 and 7 show the application of the principle of offsetting the members as applied to reversing or key blocks designed for 40 changing the order of the line blocks, and corner blocks arranged at the corners of angular wall structure. As will be understood from an inspection of the drawings, with particular reference to Figs. 1 and 2, 45 the interfitting of the adjacent blocks both in the same and adjoining courses must be effected by a transverse movement of each block with relation to those with which it is interlocked, that is to say a movement in 50 a direction parallel with the wall faces or perpendicular to the course face surfaces, and when the interlock has been effected, the angular displacement of one block with relation to the next or the others with which 55 it is interlocked is prevented even though cement or plaster may not be used in the joint, owing to the overhanging relation of the male elements at the inner end edges of the block members with the interlocked male 60 members of the outer or remote end edges of the adjoining blocks. Obviously the offsetting of the members of each block serves to guard against any shifting between the blocks in adjoining or adjacent courses and 65 hence the binding together of the elements

of the wall to effectually resist both external and internal pressure.

What is claimed is:

1. A building block for overlapping break-joint relation with similar blocks in the same and adjacent courses, the same consisting of similar reversely disposed members meeting at a common transverse plane of the block, and respectively having outer opposite wall face surfaces and provided with complementary inner interlocking faces, one of said members being offset from the other in a direction perpendicular to the course. 70

2. A building block for overlapping break-joint relation with similar blocks in the same and adjacent courses, the same consisting of similar reversely disposed members meeting at a common transverse plane of the block, and respectively having outer opposite wall face surfaces and provided with complementary inner interlocking faces, one of said members being offset from the other in a direction perpendicular to the course, said transverse meeting plane being 85 obliquely disposed to the planes of the wall face surfaces. 90

3. A building block for overlapping break-joint relation with similar blocks in the same and adjacent courses, the same consisting of similar reversely disposed members meeting at a common transverse plane of the block, and provided respectively with wall face surfaces and with complementary interlocking inner faces, the meeting plane 100 of said members being at an angle to said wall face surfaces and one of said members being offset from the other in a direction parallel with the wall face surfaces. 95

4. A building block for overlapping break-joint relation with similar blocks in the same and adjacent courses, the same consisting of similar reversely disposed members meeting at a common transverse plane of the block and respectively having 105 wall face surfaces and intersecting course face surfaces of which the former are parallel and are disposed at an angle to said meeting plane between the members, said members being provided with complementary 110 interlocking elements and one of the members being offset from the other on said meeting plane in a direction perpendicular to the course face surfaces. 115

5. A building block for overlapping break-joint relation with similar blocks in the same and adjacent courses, the same consisting of similar reversely disposed members meeting at a common transverse plane of the block and respectively having opposite longitudinal wall face surfaces at an angle to said meeting plane and each having transverse inner and outer end surfaces located at different distances from said transverse meeting plane and provided respec- 125 130

tively with male and female interlocking elements, one of said members being offset from the other member in a direction parallel with said meeting plane and parallel 5 with the wall face surfaces.

6. A building block for overlapping break-joint relation with similar blocks in the same and adjacent courses, the same 10 consisting of similar reversely disposed members meeting at a transverse medial plane of the block and each having longitudinal wall face surfaces located on opposite sides of and equal distance from a longitudinal medial line of the block, and each

having transverse inner and outer end surfaces located at different distances from said transverse medial plane and provided respectively with male and female interlocking elements, one of said members being offset from the other on said meeting plane in 15 a direction parallel with the wall face surfaces.

In testimony whereof I affix my signature in presence of two witnesses.

JOHN R. BAUMANN.
